(57) **CLAIM**

The ornamental design for a “paint applicator device,” as shown and described.

DESCRIPTION

FIG. 1 is a perspective view taken from above showing a paint applicator device;

FIG. 2 is a front view of the paint applicator device shown in FIG. 1;

FIG. 3 is a left side view of the paint applicator device shown in FIG. 1, the right side view being a mirror image thereof;

FIG. 4 is a rear view of the paint applicator device shown in FIG. 1;

FIG. 5 is a top view of the paint applicator device shown in FIG. 1; and,

FIG. 6 is a bottom view of the paint applicator device shown in FIG. 1.

Any broken lines are for illustrative purposes only and form no part of the claimed design.
